UNITED STATES PATENT OFFICE

OCTAIVE O. McBRIDE, OF MCKINNEY, TEXAS

ELECTRIC HEAD LAMP

Application filed November 17, 1931. Serial No. 575,671.

The invention relates to a head lamp and more especially to an electric head lamp.

The primary object of the invention is the provision of a lamp of this character wherein the construction thereof is such as to permit the mounting thereof upon a hat or about the head of a wearer so that the lamp will direct light from the forehead on illumination of said lamp thus eliminating the necessity of 10 the carrying of the lamp in the hand and thereby giving freedom of use of the hands of the wearer.

Another object of the invention is the provision of a lamp of this character wherein the electric batteries are mounted in a novel manner and the current supply therefrom is controlled by a switch readily accessible for the turning on or off of the lamp of the electric bulb type when the same is either worn 15 upon a hat or carried by the head of a wearer, the supporting band of the lamp being of a kind for self-adjustment for the fitting of the lamp upon the hat or head of the wearer.

With these and other objects in view, the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:—

Figure 1 is a perspective view of a soft hat showing the lamp constructed in accordance with the invention worn thereon.

Figure 2 is a perspective view of the lamp in accordance with the invention, the same being arranged for application directly to the head of a wearer.

Figure 3 is a top plan view partly in section.

Figure 4 is a sectional view on the line 4—4 of Figure 3 looking in the direction of the arrows.

Figure 5 is a sectional view on the line 5—5 of Figure 4 looking in the direction of the arrows.

Figure 6 is a sectional view through one of the battery holders.

Figure 7 is a transverse sectional view thereof.

Similar reference characters indicate corresponding parts throughout the several views in the drawings.

Referring to the drawings in detail A designates generally a soft hat of the Fedora type and upon the same is mountable the lamp constituting the present invention and hereinafter fully described.

The lamp comprises a flexible band or strap 10 preferably made from leather and includes inner, outer and intermediate plies 11, 12 and 13 respectively united at their longitudinal meeting edges through the medium of stitches 14 to provide the unitary strap. The ends of the strap have suitably connected therewith an elastic strip or section 15 which renders said band or strap 10 endless and also permits of self-adjustment thereof 60 for the fitting of the same upon a hat A or directly upon the head of a wearer.

Suitably arranged with the band or strap 10 upon the outer ply 12 of the same are the male members 16 of detachable snap fasteners, the female members 17 of which are carried by adjustable cross related crowning straps 18, these being usable when the strap or band 10 is worn directly upon the head with the straps 18 lying over the crown of the head and thus supporting the strap or band 10 comfortably in the wearing thereof directly upon the head.

Arranged at the fore portion of the band or strap 10 is a lamp housing or casing 19, 85 the same being made fast to the strap or band 10 in any suitable manner and within this housing or casing is the electric lamp bulb 20, the said housing or casing being equipped with the front lens 21 and light reflector 22 90 of conventional form.

Located at opposite sides of the band or strap 10 are battery holders, each including a retaining frame 23 for removably receiving an electric dry cell battery 24 and a releasable clip or bail 25 pivoted at 26 to said frame 23, which pivots are carried in an embracing ring 27 insulated at 28 from the frame 23. The clip or bail 25 has fitted therein an adjustable positive pole contact 29 for 100

the battery 24 while the frame 23 and ring 27 being associated with current leads 30 and 31 respectively to the lamp bulb 20, these leads being electrically insulated from each other in their arrangement in the band or strap 10 through the positioning therebetween of the intermediate ply 13 of said band or strap and an electric circuit is closed from said batteries 24 to the bulb 20 by a hand 10 operated switch 32 mounted upon a pivot 33 in the band or strap 10 directly rearwardly of the lamp housing or casing 19 with the outer end of said switch 32 exposed for manual control.

15 The clips 25 will permit the freeing of the batteries 24 from their holders on the swinging of the clip outwardly and laterally from over the positive pole ends of the battery so that these can be readily removed from 20 the holders for replacement when the occasion requires.

It will be noted that the leads 30 and 31 are confined within the band or strap 10 between the inner and outer plies 11 and 12 25 thereof with the intermediate ply 13 interposed and in this fashion such leads insulated from each other throughout their extent between the lamp housing or casing 19 and the holders 23 for the batteries 24 as will be clearly apparent. The electric circuit from the batteries 24 to the bulb 20 is opened and closed by manual manipulation of the switch 32 as will be obvious from Figures 4 and 5 of the drawings.

35 What is claimed is:—

A lamp of the character described, comprising an endless flexible band, battery holders carried at opposite sides thereof, each holder including a retaining frame for 40 movably receiving an electric dry cell battery and having a releasable bail pivoted to the frame, the frame being fitted with an embracing ring insulated therefrom, an adjustable pole contact on the bail, a lamp housing intermediate of the battery holders and upon the band, an electric lamp within the housing, normally open electric circuit connections between the lamp and said batteries, said circuit connections being confined within the 45 band, and a manually operable switch mounted in the band directly rearwardly of the housing for manual operation for opening and closing the electric circuit.

50 In testimony whereof I affix my signature.
55 OCTAVE O. McBRIDE.
